ANIMAL HABITAT MODULE

Allan H. Willinger, New Rochelle, and Jacques Le Baigue,
Westbury, N.Y., assignors to Metaframe Corporation,
Maywood, N.J.

Filed July 12, 1972, Ser. No. 271,024

Term of patent 14 years

Int. Cl. D30—06

U.S. Cl. D30—42

FIG. 1.

FIG. 2.

FIG. 3.

FIG. 4.

FIG. 5.

FIG. 1 is a front and top perspective view of an animal habitat module, showing our new design;

FIG. 2 is a left side elevational view;

FIG. 3 is a right side elevational view;

FIG. 4 is a top plan view; and

FIG. 5 is a rear elevational view thereof.

The figures are diagonally lined to indicate transparency.

We claim:

The ornamental design for an animal habitat module, substantially as shown and described.
